(57) **CLAIM**

The ornamental design for a glass top for an electronic vaporizer, as shown and described.

DESCRIPTION

FIG. 1 is a front perspective view of a first embodiment of our glass top for an electronic vaporizer;

FIG. 2 is a front elevational view thereof;

FIG. 3 is a rear elevational view thereof;

FIG. 4 is an elevational view of the right side thereof;

FIG. 5 is an elevational view of the left side thereof;

FIG. 6 is a top plan view;

FIG. 7 is a bottom plan view;

FIG. 8 is a front perspective view of a second embodiment of our glass top for an electronic vaporizer;

FIG. 9 is a front elevational view thereof;

FIG. 10 is a rear elevational view thereof;

FIG. 11 is an elevational view of the right side thereof;

FIG. 12 is an elevational view of the left side thereof;

FIG. 13 is a top plan view; and,

FIG. 14 is a bottom plan view.

The broken lines in the drawings depict portions of the glass top for an electronic vaporizer that form no part of the claimed design.
